COMBINATION WRITING DESK AND AUTO-MATIC DISPENSER FOR WRITING KIT

Peter Tailer, New York, N. Y.

Application February 12, 1954, Serial No. 28,978

Term of patent 14 years

(Cl. D52—3)

To all whom it may concern:

Be it known that I, Peter Tailer, a citizen of the United States of America, and residing at New York, county and State of New York, have invented a new, original, and ornamental Design for a Combination Writing Desk and Automatic Dispenser for Writing Kit, of which the following is a specification, reference being made to the accompanying drawing, forming part thereof.

Fig. 1 is a perspective view of a combination writing desk and automatic dispenser for writing kit looking toward the left hand corner and showing my new design; and

Fig. 2 is a perspective view of the combination writing desk and automatic dispenser for writing kit looking toward the right hand corner.

I claim:

The ornamental design for a combination writing desk and automatic dispenser for writing kit, as shown.
